METHOD AND MEANS OF MAKING HAND-MADE NECKTIES

Nathan Gold, Portland, Oreg.

Application April 12, 1937, Serial No. 136,294

7 Claims. (Cl. 223—1)

This invention relates to a method and means of manufacturing hand-made neckties and has for its principal object to provide a machine automatic in operation and which will assist an operator in hand stitching neckties accurately, efficiently and in a minimum amount of time. The invention is particularly well adapted for the manufacture of neckties of the four-in-hand type.

One of the principal objects of the invention is the provision of a stitching guide in the form of reciprocating elements which engage the tie intermittently and advance it in timed relation to the speed of the operator. Needle guides are provided in the projections to guide the sewing needle through the tie elements in such a manner as to form the stitches, and particularly the type of stitches shown and described in my co-pending application, Serial No. 51,355, filed November 25, 1935 and entitled Necktie.

Another object of the invention is the provision of means for operating the machine which may be actuated either by the foot or knee of the operator to thereby leave both hands free for stitching and otherwise dealing with the necktie.

A further object of the invention is the provision of a laterally adjustable receptacle running lengthwise of the machine which may be narrowed or widened to accommodate neckties of predetermined widths.

A still further object of the invention is the provision of means automatic in operation for securely positioning the various tie elements within the channel way and for releasing the same immediately after the stitching operation.

These and other objects will appear as my invention is more fully hereinafter described in the following specification, illustrated in the accompanying drawings, and finally pointed out in the appended claims.

In the drawings:

Figure 1 is a sectional elevation taken on line 1—1 of Figure 7, of the operating end of my machine.

Figure 2 is a view showing the release mechanism for the locking pawl shown in Figure 1.

Figure 3 is a sectional view taken on line 3—3 of Figure 1.

Figure 4 is a sectional view taken on line 4—4 of Figure 1.

Figure 5 is a sectional elevation of the idler end of my machine.

Figure 6 is a top plan view of a portion of the carrier belt, adjustable tie-receptacle and pressure fingers.

Figure 7 is a top plan view of Figure 1 with the carrier belt removed.

Figure 8 is an enlarged sectional side view of a portion of Figure 1 shown in operating position.

Figure 9 is a side elevation of a portion of the 5 operating end of my machine, showing the release mechanism for the pressure fingers.

Figure 10 is a sectional view taken on line 10—10 of Figure 9.

Figure 11 is a sectional elevation of the pressure 10 fingers and holder.

Figure 12 is a side elevation of one of the pressure fingers, detached from the holder.

Figure 13 is a top plan view of Figure 12.

Figure 14 is an enlarged sectional side elevation through the tie-elements, showing the stitch which is made on the machine as shown in Figure 8 and when advancing the tie-elements one space at a time.

Figure 15 is an enlarged section of the tie-elements, showing the stitch which is made on the machine when arranged to have three lifting points, as shown in Figure 17, and with the tie-elements advancing two spaces each time and continuing the needle straight through the elevated portions of the tie-elements.

Figure 16 is an enlarged section of the tie-elements showing the stitch which is made on the machine when arranged to have three lifting points, as shown in Figure 17, and with the tie-elements advancing two spaces each time.

Figure 17 is an enlarged view similar to Figure 8 but showing three lifting points, which are used when making the stitch shown in Figure 15 or Figure 16.

Figure 18 is a side elevation, drawn on a reduced scale, of the complete machine and showing the carrier belt in section.

Figure 19 is a top plan view of the operating end of my machine, showing a portion of a tie 40 in place and showing some of the pressure fingers holding the tie and its lining in place and also showing some of the pressure fingers in released position.

Referring now more particularly to the drawings:

The main body of the machine comprises a pair of parallel side members 1 and 2. At one end of the main body, by means of a shaft 3 I rotatably mount an idling drum 5, and at the opposite end, 50 by means of shaft 4 I rotatably mount a driving drum 6. The peripheries of both drums are formed into a series of flat portions or panels 7. An intermediate idling drum 7A is rotatably mounted on a shaft 7B. Both of said drums are 55

operatively embraced by a carrier belt, generally indicated at 8, and which consists of a series of plates 8A each mounted upon links 10 which are pivotally interconnected, as at 11. Each plate is substantially equal to the width of the flat portions of the drum for proper operative engagement therewith. Each plate of the belt is provided with opposed and adjustably mounted abutments 12 which are slotted, as shown, and mounted to the plates by set screws 13. By means of the abutments, I provide a receptacle to receive the various structural elements of a necktie, such, for instance, as the lining 14, reinforcing strip 15 and the tie-casing 16. By means of these adjustable abutments, a receptacle of various widths may be provided to accommodate any predetermined width of necktie or elements thereof.

Each plate of the carrier belt is provided with a series of apertures 17 preferably rectangular in shape, as shown. All of these apertures are in alignment with each other and the abutments are equally disposed on both sides of the line of apertures so that the apertures will lie along the center of the tie-elements when placed in the receptacle.

Along the operator's side of the machine I provide a series of pressure fingers, generally indicated at 18. The fingers are arranged in groups of three or more, as shown, and each group of fingers are handled as a unit and are embraced within a carrier 20 which is pivotally mounted as at 21 to a rocker-arm 22. The rocker-arm is pivotally mounted as at 23 to an extension 24 secured to one end of the plate 8A. The bottom wall 25 of the carrier 20 is apertured as at 26 to receive one end of a latch 27 which is pivoted as at 28 to the extension 24. When the carrier, latch and rocker-arm are in the full-line positions, shown in Figure 3, the pressure fingers 30 are in position and are bearing against the tie-elements to securely maintain them in position between the abutments 12.

As illustrated in Figures 8 and 17 the fingers are capable of yielding upwardly with the protrusion of the needles to be hereinafter described. As illustrated in Figure 11 each finger 30 is pivotally mounted to the carrier as at 31 and yieldingly mounted with respect thereto by means of a spring 32 coiled around a shaft 33 extending through the carrier. The rear portion of each finger is of channel section, and near the rear end of the channel section I form a notch 34 for removable engagement with the shaft 33 so that each finger may be removed from the carrier if necessary. The free end of the spring 32 slidably engages with a depressed portion 35 of the top surface of the finger so that each finger may be removed by merely disengaging the notch from the shaft 33 and then drawing it outwardly to disengage the spring from the depressed portion.

As previously pointed out each plate of the carrier belt is provided with a series of apertures 17 to permit the passage of locating-needle bars 36 through the plate and into engagement with the tie material to elevate and maintain the same in a position for sewing. The locating means consists of a pair of needles 37 either formed integral with, or removably secured to, the needle bars 36. The upper end of each needle bar is notched or grooved as at 36A to guide a sewing needle in an accurate path along side the needles 37. The needle bars are removably secured as at 39 to an actuating bar 40 which is slidably mounted within a stationary casing 41. The lower end of the

actuating bar is provided with a stud 42, for pivotal engagement with one arm 43 of a bell crank. The other arm of the bell crank extends upwardly from its pivot point 44 into pivotal connection as at 45 with a link 46. The opposite end of the link 46 pivotally connects as at 47 with a lever 48 pivotally mounted to the frame of the machine as at 49. The lever continues downwardly from the pivot point and terminates in an actuating arm 50 which preferably terminates within convenient reach of either the operator's knee or foot. Formed integral with the lever 48 and also pivotally mounted to the shaft 49 is a lever 51 whose free end is provided with a pawl 52 pivoted as at 53 to the arm 51 and normally held in a downward position by any suitable form of spring 53A. The arm 51 is normally held in its full line position, as shown in Figure 1, by means of a spring 54 whose one end connects, as at 55, with the arm 51, and whose opposite end is connected with one of the side members of the machine, as at 56. A ratchet-wheel 57 is secured to the driving shaft 4, and to which the drum 6 is also attached so that rotation of the ratchet-wheel will impart rotation to the drum. The pawl 52 is normally held by the spring 53A in contact with the ratchet-wheel. For rotating the drum 6 and advancing the carrier belt step by step, or one plate at a time, the lever 50 is first moved into the dotted line position, shown in Figure 1. This movement draws the pawl 52 rearwardly and allows it to drop into the next following tooth of the ratchet-wheel. When so engaged and the lever 50 is released by the operator, the spring 54 moves the lever into its normal full line position shown in Figure 1. This movement from right to left of the lower end of the arm 50 causes the upper arm 51 to move from left to right with a resultant advancement of the ratchet-wheel one notch through the medium of the pawl. When it is desired to rotate the drums or move the carrier belt freely in either direction, a cam 58 is rotated with a shaft 59 upon which it is formed. The shaft is journaled through the side walls of the machine and terminates on the outside thereof in an actuating handle 59A. Movement of the cam 58 from its full line position into its dotted line position as shown in Figure 1, lifts the pawl free and clear of the ratchet-wheel thus permitting free rotation of the drum in any direction.

To the shaft 4 I secure a sprocket-wheel 60 for rotation with the drum and ratchet-wheel. For engagement with the sprocket-wheel and for arresting its movement together with the movement of the drum and ratchet-wheel I provide a locking pawl 61 which is keyed or otherwise secured to a shaft 62 whose ends are rotatably mounted in the side walls of the machine. The outer end of the pawl 61 is formed with a lobe 63 for engagement with the sprocket-wheel as shown. When thus engaged, the pawl 61 prevents any movement or rotation of the drum 6 and ratchet-wheel 57 during the time the pawl 52 is being drawn rearwardly for re-engagement with the teeth of the ratchet-wheel. The opposite end of the pawl terminates in a projection or cam 64 arranged in the path of movement of a cam 65, formed integral with the shaft 59. The cam 58 and the cam 65 are so set with relation to each other, that when the cam 58 moves the pawl 52 into a neutral position, the cam 65 will, at the same time through the medium of the cam 64, move the pawl 61 and its lobe 63 out of engagement with the ratchet-wheel.

From the foregoing it will be seen that by rocking the arm 50 about its pivot point 49 the carrier belt will be advanced to the right step by step. Each step or movement of the belt brings 5 the apertures in the plates of the belt into alignment with the needle bars 38 which are projected upwardly through the apertures through the medium of the link 46, bell crank and actuating bar 40. The bar 40 is thrust upwardly each time 10 the arm 50 is moved into its dotted line position, as shown in Figure 1.

As previously pointed out the various elements 15 of the necktie, such as the lining, reinforcing strip and tie casing, are first arranged within the receptacle or guideway formed between the abutments 12. When thus positioned, the pressure fingers 30 are then advanced inwardly and downwardly into firm engagement with the tie elements thus holding them securely in place. 20 Then as the machine is actuated through the lever 50, the needles 37 are projected up through the apertures, through all of the tie-elements and beyond the same as shown in Figures 8 and 17. As shown in those figures the tie material is 25 moved upwardly from the carrier belt into a convenient sewing position. The resilient movement of the pressure fingers 30 is such that they will yield upwardly along with the tie material only up to a certain limit as defined by the top edge 30 66 of the carrier 20. The carrier, however, is prevented from moving upwardly by the latch 27, as shown in Figure 3. It will be noted that the fingers 30 are allowed a predetermined amount of resilient movement within the carrier 20 between the top edge 66 and the bottom edge thereof. The limited upward movement of the fingers 30 depresses the tie material between the needles 37 to thereby present areas 67 to be stitched. 35

With reference to Figure 19 it will be seen that 40 as the stitching progresses those fingers which had been previously engaged with the tie are released and moved away from the finished portion of the tie. The releasing and rearwardly moving of the carrier and fingers is accomplished 45 by a fork having two fingers 68 and 69 (see Figure 10). The fork is formed integral with a bell crank arm 70. The opposite arm 71 of the bell crank is connected by a link 72 with a lever 73 which is keyed or otherwise secured to the shaft 50 49 whose one end projects through the frame member and terminates in a bearing 74. Accordingly, as the lever 50 is moved and the shaft 49 is rotated, the forked arm 70 of the bell crank is moved from its full to dotted line position. 55 Such movement brings the fork 69 into contact with the latch 27 which disengages it from the carrier, thus freeing the carrier for its upward movement. Progressively the fork 68 then contacts the rocker-arm 22 and moves it into its dotted line position which draws the carrier rearwardly and away from the tie material, as best 60 illustrated at the right-hand end of Figure 19.

In Figure 8 I have shown two needles projecting upwardly through the necktie material 65 and elevating the same into a position to be sewed. By using two needles, I form a stitching as shown in Figure 14. This stitch is accomplished by first advancing the sewing needle 75 through the material from the right to the left, 70 as shown in Figure 8, after, of course, the thread has been knotted or otherwise secured, as at 76, to the material. The sewing needle 75 is advanced entirely through the material and the thread is drawn through with it after first forming a loop 77 at the starting of the sewing opera- 75

tion. After the loop has been formed and the thread has been advanced entirely through the material, the arm 50 is actuated and this withdraws the needles 36 from the apertures 17 and the carrier belt is advanced to the right, as viewed 5 in Figure 8, to the distance between two of the apertures so that the next time the needles 36 are projected the needle on the right, designated as A will be projected through the aperture through which the needle, designated B, had been 10 previously projected. Then the needle B will be projected in the next following aperture. In other words, the carrier belt is advanced one aperture at a time. By this, I mean that an aperture will first receive, for example, the needle 15 B, and in the next operation will receive the needle A. Thus withdrawing the needle A from the part of the tie already stitched and advancing it through the part of the tie previously and only partially stitched over needle B, the operator merely loops the thread back over the 20 previously stitched portion to complete the loop and then advances to the next needle. Thus by forming a stitch of this type I securely lock the tie elements together between the loop portions 25 of the stitch and each stitch is interconnected with the other. This particular type of stitching is best shown and described in my co-pending application, Serial No. 51,355, filed November 25, 1935 and entitled Necktie. 30

In the form illustrated in Figure 17, I provide three needles instead of two and for convenience of description, I have designated these needles as C, D and E. By using the three needles I accomplish the forms of stitching illustrated in Figures 15 and 16. The form shown in Figure 15 is an ordinary basting stitch and to accomplish this form of stitching it is merely necessary to advance the sewing needle 75 straight through the elevated portions of the tie to be sewed without 40 any looping except at the beginning of the stitching operation, as indicated at 78. When the needle 15 has passed entirely through all three elevated portions of the tie to be sewed the locating needles are then dropped downwardly and the 45 carrier belt is advanced to present three following apertures to receive the three needles on their next upward movement. By this arrangement, I position the locating needles to accomplish three stitches with each movement of the arm 50. 50

The form of stitching shown in Figure 16 consists of first a loop stitch then a basting stitch and again a loop stitch and so on throughout the length of the tie. This form of stitching is also accomplished by using the three needles 55 and in so doing the thread at the beginning is looped to secure its end and the needle is advanced entirely through the three elevated portions of the tie to be sewed. That portion of the tie over the center needle is sewed with a 60 basting stitch while the portions over the two end needles are sewed with a loop stitch. When the three stitches thus described are accomplished, the three needles are dropped and the carrier belt is advanced to present two new apertures for C and D but needle E projects upwardly 65 through the aperture previously occupied by the needle C. This brings that portion of the tie which was only partly sewed over the needle C into a position for completing the loop stitch at 70 the beginning of the next series of three stitches. The sewing needle is again advanced as aforesaid, to form a basting stitch over the center needle and a partial stitch over the last needle. The grooves or notches 36A in the top of the needle 75

bars are in alignment with each and form a convenient guide for the sewing needle.

By elevating portions of the tie to be sewed, as shown in Figures 8 and 17, I am enabled to quickly, efficiently and accurately form a series of interconnected hand-made stitches with a reserve of thread between them.

While I have shown a particular form of embodiment of my invention, I am aware that many minor changes therein will readily suggest themselves to others skilled in the art without departing from the spirit and scope of the invention. Having thus described the invention, what I claim as new and desire to protect by Letters

15 Patent is:—

I claim:

1. A machine for manufacturing neckties comprising an endless belt, receptacles formed in the belt for receiving structural elements of a necktie, means for maintaining the elements within the receptacle, a plurality of stitch-locating members adapted to be progressively projected through the belt and into engagement with the tie-elements, and means for advancing the belt and tie-elements.

2. A machine for manufacturing neckties, comprising an endless carrier belt, a laterally adjustable receptacle formed in the belt for receiving structural elements of a necktie, means for maintaining the tie-elements within the receptacle through a predetermined distance of travel of the carrier belt, a plurality of stitch-locating needles adapted to be progressively projected through the belt and through the tie-elements, and means for advancing the carrier belt upon withdrawing the locating needles from the belt.

3. A machine for manufacturing neckties, comprising an endless carrier belt, a laterally adjustable receptacle formed in the belt for receiving structural elements of a necktie, means for maintaining the tie-elements within the receptacle through a predetermined distance of travel of the carrier belt, said means comprising a plurality of yieldingly mounted fingers, a plurality of stitch-locating needles adapted to be

progressively projected through the belt and through the tie-elements and to elevate portions of the tie-elements into a position to be hand-stitched, and means for advancing the carrier belt upon withdrawing the locating needles from the belt.

4. A machine for manufacturing neckties, comprising an elongated frame, an endless carrier belt running lengthwise around the frame, automatically releasable fingers formed on the belt for positioning the necktie elements lengthwise of the belt, a plurality of needles adapted to be moved through the belt and through the tie-elements and for elevating portions of the tie-elements into a position to be hand-sewed, and means for advancing the belt.

5. A machine for manufacturing neckties, comprising a movable necktie supporting platform having an adjustable necktie receptacle formed lengthwise thereof, a needle operating mechanism adapted to project a plurality of needles through the platform and through necktie elements disposed within the receptacle, said needles adapted to elevate portions of the necktie elements into a position to be sewed.

6. A method of sewing a necktie with a series of interconnected hand-made stitches consisting in elevating portions of the tie-elements into spaced transverse ridges, depressing the portions of the tie-elements between the ridges, and advancing a sewing needle and thread in a straight line through said ridges then returning the needle and thread and again advancing through one of said ridges to form a loop stitch therein.

7. A machine for manufacturing neckties, comprising an endless carrier belt, means formed on the belt for receiving elements of a necktie, a plurality of needles adapted to be projected through the belt and through the tie-elements, means intermediate the needles for depressing portions of the tie-elements between the needles, means for intermittently advancing the needles through the belt and the tie-elements and for withdrawing the needles therefrom, and means for advancing the carrier belt and tie-elements.
